CAR CARRIER CASE

Paul Belokin, Jr., 6919 W. 43rd St.,
Berwyn, Ill. 60402

Filed Mar. 24, 1969, Ser. No. 16,400

Term of patent 14 years

Int. Cl. D12—14; D3—01

U.S. Cl. D14—27

FIG. 1 is a perspective view of the car carrier case with a portion of a car trunk shown in dotted lines for illustration only;

FIG. 2 is a perspective view showing the bottom of the car carrier case;

FIG. 3 is a perspective view of the car carrier case showing the slide fastener open and the side panel in open position;

FIG. 4 is a bottom plan view of the car carrier case;

FIG. 5 is a top plan view of the car carrier case;

FIG. 6 is a bottom edge view of the car carrier case; and

FIG. 7 is an end view of the car carrier case.

I claim:

The ornamental design for a car carrier case, as shown and described.
